(57) **CLAIM**

The ornamental design for a coating machine, as shown and described.

DESCRIPTION

FIG. 1 is a front elevation view of a coating machine according to our new design;

FIG. 2 is a rear elevation view of the coating machine of FIG. 1;

FIG. 3 is a left side view of the coating machine of FIG. 1;

FIG. 4 is a right side view of the coating machine of FIG. 1;

FIG. 5 is a top view of the coating machine of FIG. 1;

FIG. 6 is a bottom view of the coating machine of FIG. 1;

FIG. 7 is a front elevation view of a second embodiment of the coating machine according to our new design;

FIG. 8 is a rear elevation view of the coating machine of FIG. 7;

FIG. 9 is a left side view of the coating machine of FIG. 7;

FIG. 10 is a right side view of the coating machine of FIG. 7;

FIG. 11 is a top view of the coating machine of FIG. 7;

FIG. 12 is a bottom view of the coating machine of FIG. 7; and,

FIGS. 13 and 14 are perspective views of the coating machine of FIG. 7.

The broken lines in FIGS. 1–14 are for illustrative purposes only and do not constitute part of the claimed design.
